RETHREADING DIE

Earl R. Koonz, Greenfield, Mass., assignor to
Greenfield Tap & Die Corporation, Greenfield,
Mass., a corporation of Massachusetts

Application June 4, 1932. Serial No. 615,393

2 Claims. (Cl. 10—116)

This invention relates to thread cutting dies which are particularly designed for re-cutting worn or damaged screw-threads.

It is the general object of my invention to provide an improved construction of re-threading die for such purposes, so designed that it may be easily applied to the work and quickly seated in the original threads.

I also provide means to cause the separable parts of the die to yieldingly engage the work and to retain their position thereon during the application of a die-stock thereto.

My invention further relates to arrangements and combinations of parts which will be hereinafter described and more particularly pointed out in the appended claims.

A preferred form of the invention is shown in the drawing, in which

Fig. 1 is a plan view of a die-stock containing my improved re-threading die;

Fig. 2 is a plan view of the die itself;

Fig. 3 is a side elevation, looking in the direction of the arrow 3 in Fig. 2, and

Fig. 4 is a plan view, partly in section, and looking in the direction of the arrow 4 in Fig. 2.

Referring to the drawing, my improved re-threading die comprises a pair of die blocks 10 adapted to be assembled in the usual die holder 11 and having peripheral depressions 12 to receive the pointed inner ends of clamping and adjusting screws 13.

The die blocks 10 are provided with the usual cutting sections 15, spaced apart by recesses or clearance openings 16. The cutting sections 15 are preferably provided with both forward and rearward cutting faces and the teeth are formed without clearance, so that the die will cut equally well in either direction.

A groove or recess 20 is formed in one end of each die block 10 and a flat spring plate 22 is secured in the recesses 20 by screws 24.

The method of use and the advantages of my improved re-threading die are clearly disclosed in Fig. 4, where the die is shown mounted on a bolt B having threads which have been bruised in their outer end portion. When such a screw

thread is to be re-cut, I spring the die blocks 10 apart sufficiently so that the re-threading die can be slipped over the damaged end threads and accurately seated on the uninjured threads away from the end of the bolt. The spring 22 permits the die blocks to be thus spread apart for application to the bolt but yieldingly holds the die blocks 10 in assembled relation on the bolt while the stock 11 is applied to the die blocks 10 and the screws 13 are adjusted to cause the die blocks to closely engage the uninjured threads on the bolt B.

The re-threading die is then rotated by the stock 11 in such a direction as to cause the die to cut toward the end of the bolt, thus avoiding the difficulty of starting the die on bruised threads, with the usual result of cross-threading.

The spring plate 22 permits a slight relative movement of the die blocks 10 to adjust themselves to the sometimes irregular screw-threads to which they are applied.

As the toothed sections 15 have both forward and rearward cutting faces, my improved re-threading die may be used as above described, cutting outward from the inner end of the bolt thread, or may be used by starting at the end of the bolt and cutting the thread in the usual way. The latter method of operation is preferable when the extreme end threads are uninjured and the thread may be easily caught.

Having thus described my invention and the advantages thereof, I do not wish to be limited to the details herein disclosed, otherwise than as set forth in the claims, but what I claim is:—

1. A re-threading die comprising two die blocks with flattened end portions, and a light flat leaf spring having its ends secured to said flattened end portions and substantially within the periphery of said die blocks.

2. A re-threading die comprising two die blocks provided with end grooves, and a light flat leaf spring member secured in said end grooves substantially within the periphery of said die blocks and holding said die blocks yieldingly in assembled relation.

EARL R. KOONZ.
